UNITED STATES PATENT OFFICE.

OSSIP JOSEPH WALINSKY, OF SEA GATE, NEW YORK, ASSIGNOR TO WHITE LUGGAGE CO. INC., OF NEW YORK, N. Y., A CORPORATION OF NEW YORK.

DESIGN FOR A SUITCASE.

Application filed April 22, 1926. Serial No. 17,339. Term of patent 14 years.

To all whom it may concern:

Be it known that I, OSSIP JOSEPH WALINSKY, a citizen of the United States, residing in Sea Gate, county of Queens, and State of New York, have invented a new, original, and ornamental Design for Suitcases, of which the following is a specification, reference being had to the accompanying drawing, forming part hereof.

The drawing is a perspective view of a suitcase showing my new design.

I claim:

The ornamental design for a suitcase as shown.

OSSIP JOSEPH WALINSKY.
